COMBINED DRESSER, CLOTHES SUPPORT AND SHOE RACK

William H. Armstrong, Birmingham, Mich., assignor to Borg-Warner Corporation, Chicago, Ill., a corporation of Illinois

Filed Aug. 28, 1962, Ser. No. 71,479

Term of patent 14 years

(Cl. D33—6)

FIG. 1 is an isometric view of a combined dresser, clothes support and shoe rack showing my new design;

FIG. 2 is a side elevation thereof illustrating the configuration of each side thereof; and

FIG. 3 is a back elevation thereof.

I claim:

The ornamental design for a combined dresser, clothes support and shoe rack, substantially as shown and described.
